JOSEPH WILLARD GAMBLE AND AXEL BLYTT WALLEM, OF PHILADELPHIA, PENNSYLVANIA, ASSIGNORS TO JOSEPH S. LOVERING WHARTON, WILLIAM S. HALLOWELL, AND JOHN C. JONES, DOING BUSINESS UNDER THE FIRM-NAME OF HARRISON SAFETY BOILER WORKS, OF PHILADELPHIA, PENNSYLVANIA.

HEATER AND SEPARATOR.

996,577.

Specification of Letters Patent. Patented June 27, 1911.

Application filed April 21, 1909. Serial No. 491,285.

To all whom it may concern:

Be it known that we, JOSEPH WILLARD GAMBLE and AXEL BLYTT WALLEM, citizens of the United States, and residents of the 5 city and county of Philadelphia and State of Pennsylvania, have invented certain new and useful Improvements in Heaters and Separators, of which the following, taken in connection with the accompanying drawings, is a concise and complete description thereof.

This invention particularly relates to certain improvements in a construction described and claimed in a co-pending application, serially numbered 431,271, filed May 6th, 1908.

The chief object of our present invention is to provide improved means for cutting out of communication with the heater, the 20 separator and overflow chambers thereof, in order that one may be afforded the opportunity of cleaning the heater with perfect safety, free from any liability of the water or steam within the overflow chamber 25 being forced back into the heater, which is the case when the separator chamber is in direct communication with the overflow chamber by a drip connection, through which, (in the event that the inlet to the 30 heater is closed) the pressure of steam within the separator is communicated and exerted upon the water or steam in the overflow, thus forcing the same back into the heater.

35 A further object of our invention is to render it impossible to cut off or interrupt the overflow from the heater when the same is in operation.

To the accomplishment of these, as well 40 as other objects, we have illustrated in the accompanying drawings, and described in the following specification, a structure that we may employ in carrying out our invention. We would have it understood, however, that we are not limited in respect to 45 the manner in which we accomplish our objects, since other equivalent means may be employed without departing from the scope and tenor of our claims.

50 Referring to the annexed drawings, in which like reference numerals indicate like parts throughout the respective views; Figure 1 represents so much of a combined heater and separator, partly in section, as is

necessary to illustrate one form of our present invention, in which mechanism is employed for successively or simultaneously operating the exhaust inlet and overflow valves. Fig. 2 is a view in which we have illustrated the operation of the valve controlling mechanism.

Referring to Fig. 1 of the drawings in detail, —1— indicates a portion of the wall or shell of a heater.

—2— indicates the separator, and —3— 65 indicates the overflow or outlet to waste. The heater is provided with an exhaust inlet opening, —4—, leading from the separator —2—, and an overflow outlet —5— leading to the overflow chamber —3—. Within 70 the separator —2— is provided a baffle —6—, indicated by dotted lines. The separator is also provided with an auxiliary outlet —7— leading to a heating system or other point of use (not shown).

—7^a— indicates a deflecting plate connected to the baffle.

—8— indicates the separator drain or drip connection to the overflow or outlet chamber —3—.

9 indicates a skimmer within the heater down through which the overflow water is passed to waste, this being of usual and well known construction.

Both the exhaust inlet —4— and the overflow outlet —5— are controlled by rotary valves —10— and —11— respectively. These rotary valves are connected through intermediate mechanism, and operate successively or simultaneously. The manner in 90 which these valves are constructed, mounted, and operated, is substantially in accordance with the following detailed description: Rotatively mounted outside the heater proper, is a spindle —12— upon which is keyed, or 95 otherwise suitably connected, a collar retaining member —13— carrying a screw threaded shaft —14— which is connected to and operates the valve —10—.

—15— indicates a packing box through 100 which the spindle —12— is journaled.

—16— is a spring, interposed between the valve —10— and the projecting flange on the collar retaining member —13— for an obvious purpose.

Fastened to the shaft —12— is an arm —17— having at its outer end a projecting pin or stud —18—.

—19— indicates a spindle mounted in the casing of the overflow chamber —3—. To this spindle is suitably fastened the rotary valve —11— controlling the overflow port 5 or outlet —5—.

—20— indicates an arm or crank keyed to the spindle —19—.

—21— indicates a link pivoted to the arm —20— at one end and connected 10 through slot connection —22— at its other end to the projecting pin or stud —18— of the arm —17—.

—23— indicates an operating lever suitably fastened upon the spindle —19—.

15 —24— indicates a guide plate provided with suitable stops for limiting the movement of the operating lever.

Supposing both exhaust inlet and overflow valves are open, the exhaust steam will 20 enter the separator in the direction indicated by the arrow A, impinging and passing around baffle plate —6—, and through inlet —4— into the heater, where it contacts with and heats the water admitted thereto by any 25 suitable supply. The overflow from heater passes down through passageway —9— through exit opening —5— into overflow chamber —3—. When the valves are closed, as shown, the exhaust steam, after contact- 30 ing with the baffle —6— is passed directly up through auxiliary outlet —7— and indicated by arrow B to another point of use. The entrained oil, water, or other separated matter which has been separated from the 35 exhaust steam within the separator, is led to the overflow chamber through drip connection —8—. When the heater has been cut out by reason of both valves being closed, it will be readily seen that any pres- 40 sure that may be created within the separator and acting through the drip connection upon the water in the overflow chamber, cannot force it back into the heater, hence the cleaning operation of the heater 45 can be accomplished without interference. It will be further apparent from this description that when the exhaust inlet valve to the heater is open, and the overflow valve is open, there is secured a free overflow passage 50 at all times when the heater is in operation.

The detailed operation of the valves and operating mechanism, is as follows, reference being had to Figs. 1 and 2 of the drawing:—It will be noted that three positions of the valves and mechanism are shown;—in closed position, (Fig. 1); and partial and full opening of the pilot valve 11 before the exhaust inlet valve —10— begins to open 55 (Fig. 2). When the lever —23— is operated to open the valves, the arm —20— being keyed and fast to shaft —19— will rotate therewith. This will cause the link —21— having the slot connection with the 60 arm —17— (which allows a sufficient

amount of lost motion to operate the valves in the manner desired,) to vertically move, until it becomes substantially perpendicular as shown in full in Fig. 2. In this position, the pressure of the exhaust steam is 70 permitted to enter into the heater through passageway —5—, and there exert an equal pressure against the inner face of the valve —10— to that exerted on the separator side of said valve, and thus facilitate and ease 75 the operation of the exhaust inlet valve —10—. Upon further operation or rotation of the operating lever —23—, further lost motion is permitted by reason of the slot connection of parts —17— and —21—, 80 until the upper end of the slot —22— engages the pin or stud —18—. In this position, the pilot valve —11— is almost completely opened, while the exhaust inlet valve still remains closed. Now upon further operation or rotation of the operating lever, the exhaust steam inlet valve —10— will 85 operate to open the inlet. Thus, we accomplish the opening of the two valves successively in a manner that minimizes the 90 amount of requisite force or power. It will be further noticed that when the valves are in a closed position that the pilot valve is locked by reason of the parts —20— and —21— having passed their common aligned 95 position, (as shown in dotted lines in Fig. 2,) so that the weight of the parts will tend to hold the pilot valve —11— in closed position by reason of gravity.

We do not wish to be understood to be 100 restricting ourselves to the successive operation of these valves; but on the contrary, we may, if we so desire, operate the two valves simultaneously.

Where we have used the term “overflow 105 chamber” we mean any overflow into and through which may be discharged the separated waste products of the separator or surplus water from the heater or both, and as a special type of overflow chamber, we 110 would mention the well known form of steam trap.

It will be understood that we do not wish to be restricted to the specific several embodiments of our invention. We may de- 115 part therefrom without departing from the spirit and scope of our invention.

Where we have used the words “combined heater and separator,” we mean that both the heater and separator form part of the 120 same structural unit. Where we have used the words “unitary structure,” we mean that the component parts, such, for instance, as the heater and separator and overflow, form part of the same structural unit. 125

While we have illustrated and described our invention as applied to a feed water heater, we would have it distinctly understood that we are not limited to this specific embodiment, as it is manifest that a re- 130

ceptacle of any kind wherein it is desired to utilize exhaust steam may be employed without departing from the scope and tenor of our appended claims.

5 Having thus described our invention, what we claim as new herein, and desire to protect by Letters Patent, is:

1. The combination of a heater having a water sealed overflow chamber, and a separator; a drip connection for said separator, connected to the overflow chamber; and means comprising a plurality of connected valves for successively cutting out the separator and overflow chamber from communication with said heater.

10 2. The combination of a heater having a water sealed overflow chamber; a separator, provided with an auxiliary outlet; passageways intermediate and connecting separator, overflow chamber and heater; valves controlling two of said passageways, and mechanism intermediate and connecting said valves for operating them coöperatively.

15 3. The combination of a heater having an overflow chamber; a separator; communicating passageways between separator, overflow chamber and heater; a valve controlling the passageway from the separator to the heater; a valve controlling the passageway from the heater to the overflow chamber; and mechanism connecting said valves for successively operating them.

20 4. A unitary structure comprising a heater provided with an inlet and an overflow; valves controlling said inlet and overflow, and means for successively operating said valves.

25 5. A heater provided with an inlet; an overflow; controlling valves for said inlet and overflow, and connecting means between said valves adapted to operate the one after the other has come to rest.

30 6. A heater provided with an exhaust steam inlet; an overflow; valves controlling said inlet and overflow; means for operating said valves, said means comprising a plurality of connecting arms and a link and means for moving said arms and link, to cause the inlet valve to remain seated until the overflow valve is open.

35 7. A heater provided with an inlet and outlet; valves controlling said inlet and outlet; and means connecting said valves for moving said valves successively, simultaneously and in inverse succession.

40 8. A heater provided with an inlet and an outlet; rotatably mounted valves controlling said inlet and outlet; a pair of arms connected to said valves; a slotted connecting link pivoted to one of said arms and engaging the other of said arms by a slot connection.

9. A heater provided with a plurality of passageways; valves controlling said passageways; a plurality of connecting arms 65 and a link connecting said valves; said link provided with a slot connection to provide lost motion to move said valves successively, simultaneously and in inverse succession.

10. A heater provided with an inlet and 70 an outlet; valves controlling said inlet and outlet; a plurality of connecting arms and a link connecting said valves; one of said arms and said link provided with a slot and pin connection; and means for operating 75 said arms and link.

11. A heater provided with an inlet and overflow; valves controlling said inlet and overflow; and means connecting said valves for simultaneously operating them. 80

12. A heater provided with an inlet and overflow; valves controlling said inlet and overflow; and means connecting said valves for operating them.

13. The combination of a heater provided 85 with an inlet and an overflow; valves controlling said inlet and overflow, and connecting means for operating said valves in unison.

14. The combination of a heater provided 90 with an inlet and an overflow, and connected valves coöperatively controlling said inlet and overflow.

15. The combination of a separator and receptacle, connected by a passage, with said 95 separator; an overflow from said receptacle; valves controlling said passageway and overflow, and means connecting the said valves for operating the same.

16. The combination of a separator and 100 receptacle connected by a passage in said separator; an overflow from said receptacle; a passage between the separator and the overflow; a valve in the passageway between the separator and the receptacle; a 105 valve in the overflow, and means connecting said valves for operating the same together.

17. A feed water heater provided with a shell, means for supplying water to the interior of the shell, a steam inlet, a passage 110 for leading a portion of the steam into contact with the water to be heated, a valve for varying the amount of steam admitted through said passage, an outlet for the remaining portion of the steam, an overflow, 115 and a valve, operatively connected with the first-named valve, controlling the connection from the interior of the shell to the overflow.
